UNITED STATES PATENT OFFICE.

PAUL CASPARY, OF CHICAGO, ILLINOIS.

DESIGN FOR A BRACELET FOR A SHOE.

49,737.

Specification for Design.

Patented Oct. 10, 1916.

Application filed July 31, 1916. Serial No. 112,472. Term of patent 3½ years.

To all whom it may concern:

Be it known that I, PAUL CASPARY, a citizen of the United States, residing at Chicago, in the county of Cook and State of Illinois, have invented a new, original, and ornamental Design for Bracelets for Shoes, of which the following is a specification, reference being had to the accompanying drawings, forming a part thereof.

In the drawings the figure is a perspective view of a bracelet, illustrating my new design.

I claim:
The ornamental design for a bracelet for a shoe, as shown.

PAUL CASPARY.
